ATTORNEY.

UNITED STATES PATENT OFFICE.

JAMES M. COMBS, OF AKRON, OHIO.

BATHING-SUIT OR LIFE-PRESERVER.

1,314,185.

Specification of Letters Patent. Patented Aug. 26, 1919.

Application filed December 5, 1918. Serial No. 265,368.

To all whom it may concern:

Be it known that I, JAMES M. COMBS, a citizen of the United States, residing at Akron, in the county of Summit and State 5 of Ohio, have invented new and useful Improvements in Bathing-Suits or Life-Preservers, of which the following is a specification.

This invention relates to improvements in 10 inflatable bathing suits or life preservers so constructed that when inflated sufficient buoyancy is afforded by the suit so as to sustain a person in the water. The device embodies a slip-on suit provided with an 15 opening for the neck and the arms and legs and divided into a plurality of compartments capable of being substantially simultaneously inflated whereby the proper displacement is obtained for floating a person 20 in the water.

An object of the invention is to provide a suit of the type described comprising a plurality of separate compartments all connected, said suit comprising a pair of spaced 25 walls of substantially water or air proof material, and provided with an inflating tube by which the inflation of the suit is secured.

Furthermore, an object is to provide a 30 suitable pocket on the garment within easy reach of the wearer wherein the inflating tube may be stored when not in use to permit the compact folding up of the suit when deflated.

With the foregoing and other objects in 35 view, the invention consists in the novel construction, combination and arrangement of parts constituting the invention to be herein-after specifically described and illustrated 40 in the accompanying drawings which form a part hereof wherein is shown the preferred embodiment of the invention, but it is to be understood that changes, variations and modifications can be resorted to which come 45 within the scope of the matter hereinafter claimed.

In the drawings in which similar reference numerals indicate like parts in the different figures,

50 Figure 1 is a perspective view of a combined bathing suit and life preserver embodying the present invention.

Fig. 2 is an enlarged front elevation of the 55 upper portion of the suit shown in Fig. 1, to better illustrate the construction of the same.

Fig. 3 is a similar view taken below the view shown in Fig. 2, and

Fig. 4 is a longitudinal sectional view of the device shown in Fig. 1.

The suit which comprises the present invention is fashioned in the general conventional form of a bathing suit provided with an opening 1 for the neck of the wearer, arm openings 2 and leg openings 3 and is open along the front from the crotch to the neck, 60 the two side members of which are capable of being secured together by fastening means such as buttons 4. The entire suit comprises inner and outer walls 5 and 6 respectively which are fastened together by spaced rows 65 of stitching to form a plurality of compartments preferably arranged so that the rows of stitching extend longitudinally of the entire garment and also transversely thereby providing substantially square compartments 70 over the entire device. To illustrate briefly the construction of the upper portions of the garment is provided with a plurality of spaced vertical rows of stitching 7 and a plurality of transverse or longitudinal spaced rows of stitching 8 which intersect the rows of stitching 7 to thereby divide the garment into spaces or compartments 9. This is better illustrated in Fig. 2 wherein 75 the stitching is shown enlarged and it will be pointed out that at the intersections of 80 of the longitudinal and circumferential rows of stitching the stitching is interrupted at points 10. These interruptions taking place at substantially all and the most conveniently arranged positions near the intersections of the stitching. The stitching between the two walls 5 and 6 is intended to 85 form a substantially air tight joint or union to prevent the escape of air excepting 90 through the openings 10 and at the same time to hold the two walls 5 and 6 together and to provide when the device is inflated a series of substantially elliptical compartments 95 11 (see Fig. 4). It is contemplated 100 that the interruptions in the stitching will occur so that the air forced into one compartment in the upper portion of the garment will flow through the interruptions in the stitching and gradually and almost simultaneously inflate them. One of the compartments, 12 for example, is provided with an 105 inflating stem 13 to which is connected a flexible tube 14. Air may be forced through the tube 14 by the user of the device or by a 110

suitable pump as desired, and the air flows into the various compartments gradually filling them, through the connecting openings between the compartments formed by the interruptions in the stitching forming the compartments. In order to cover the inflating stem 13 I provide a pocket 15 which is shown in Fig. 1 in its permanent position and which is bent away in Fig. 2 to show the position of the inflating tube. At approximately the waist line of the garment is a circumferential compartment 16 which is not interrupted by longitudinal stitches but is formed by circumferential or horizontal stitches 17 spaced apart to provide a belt-like compartment. The interior of the chamber 16 connects with the compartments above by means of the interrupted stitching forming openings 18. Below the circumferential compartment 16 the compartments 19 are formed in a similar manner and are fashioned substantially the same as the compartments above the member 16. At a point approximately at the upper ends of the leg portions of the garment the walls are divided into smaller compartments 20 by longitudinal stitching 21 and circumferential stitching 22 so that the compartments from the upper portions of the legs of the garment to its lower end are considerably smaller than the compartments which are arranged around the waist and torso portion of the garment. The stitching between all of the compartments 19 is interrupted at each intersection of the rows of stitching as at 23 to permit the air or inflating fluid to pass downwardly into all the compartments of the garment. The inflating fluid in the compartments 19 passes through openings 24 into the smaller compartments 20 in the leg portions of the device. It is intended that the size of the compartments in cross section in the leg portions will be much smaller than those in the upper portion as less buoyancy is required for supporting the legs than the chest or body portion of the wearer. In use the inflation of the compartments above the circumferential compartment 16 causes them all to expand rapidly and the inflating fluid passing from the compartment 16 into the compartments 19 passes into the smaller compartments 20 in the leg portions so that while not precisely simultaneously inflated, the inflation is rapid and easily secured.

I claim,

1. A bathing suit or life preserver comprising a garment having inner and outer walls formed of approximately air proof material, said walls united by rows of stitch-

ing, said rows of stitching extending in spaced relation longitudinally and in spaced relation circumferentially of the garment to divide said garment into compartments the boundaries of which are formed by said stitching, the intersections of the stitching between the walls being interrupted to permit the flow of an inflating fluid between the various compartments whereby the introduction of a buoyancy fluid into a selected compartment is enabled to pass to all portions of said garment.

2. A bathing suit or life preserver comprising a garment having inner and outer walls formed of approximately air proof material, said walls united by rows of stitching, said rows of stitching extending in spaced relation longitudinally and in spaced relation circumferentially of the garment to divide said garment into compartments the boundaries of which are formed by said stitching, the intersections of the stitching between the walls being interrupted to permit the flow of an inflating fluid between the various compartments whereby the introduction of a buoyancy fluid into a selected compartment is enabled to pass to all portions of said garment, the dimensions of the compartments at the lower or leg portions of said garment being smaller than the compartments at torso forming portion of the garment.

3. A life preserver comprising a garment having body and leg portions of double ply construction, spaced rows of longitudinal and circumferential stitching between the plies forming air receiving compartments, the rows of stitching in the leg portions being in close relationship, thereby to provide compartments of reduced size compared with the main body portion of the garment.

4. A life preserver comprising a garment having body and leg portions of double ply construction, spaced rows of longitudinal and circumferential stitching between the plies forming air receiving compartments, the longitudinal stitching being interrupted adjacent the waist line of the garment to provide a continuous air passage encircling the body, the intersections of the stitching being interrupted to provide communication between all of said compartments and waist line air passage, and inflating means associated with one of said compartments whereby all of said compartments and waist line air passage are simultaneously inflated.

In testimony whereof I have hereunto set my hand.

JAMES M. COMBS.
